UNITED STATES PATENT OFFICE.

SIDNEY R. MILBURN, OF WEEHAWKEN, NEW JERSEY.

DESIGN FOR A WATCH-HOLDER.

45,393.

Specification for Design.

Patented Mar. 10, 1914.

Application filed November 12, 1913. Serial No. 800,684. Term of patent 3½ years.

To all whom it may concern:

Be it known that I, SIDNEY ROBERT MILBURN, a citizen of the United States, residing at Weehawken, in the county of Hudson and State of New Jersey, have invented a new, original, and ornamental Design for a Watch-Holder, of which the following is a specification, reference being had to the accompanying drawings, forming part thereof.

Figure 1 is a front perspective view of the

watch holder showing my new design, and Fig. 2 is a back perspective view of the same.

I claim:

The ornamental design for a watch holder as shown.

SIDNEY R. MILBURN.

Witnesses:

E. F. STRICKLAND,
N. G. KEATING.
